UNITED STATES PATENT OFFICE.

GRAHAM GROSVENOR AND FREDERIC A. COOLIDGE, OF NEW YORK,
N. Y., ASSIGNORS TO OTIS ELEVATOR COMPANY, OF JERSEY CITY,
NEW JERSEY, A CORPORATION OF NEW JERSEY.

GRINDING APPARATUS.

No. 852,021.

Specification of Letters Patent.

Patented April 30, 1907.

Application filed May 27, 1905. Serial No. 262,549.

To all whom it may concern:

Be it known that we, GRAHAM GROSVENOR and FREDERIC A. COOLIDGE, citizens of the United States, residing in the borough of Manhattan, county of New York, and State of New York, have invented a new and useful Improvement in Grinding Apparatus, of which the following is a specification.

This invention relates to a machine designed for grinding surfaces whether in the same or in angularly related planes, and it provides an apparatus in the nature of an appliance particularly adapted for grinding or similarly preparing elevator guide surfaces particularly the portions contiguous to the abutting ends of the assembled sections at the connecting joints therebetween.

The present apparatus is adapted for use while temporarily affixed or secured to one of the sections or lengths of the guide (the several sections being assembled in position vertically of the elevator well) adjacent to the joint between such section and the contiguous section and enables the operator by manipulation of the power-driven grinding wheel to smooth up the surfaces at the joint, and thereby bring the guide surfaces fair with each other even though (as is generally the case) they are out of alinement with each other as the result of carelessness in construction, constructional defects, or economies in erection.

A grinding apparatus constructed according to the present invention, embodies a grinding wheel, a clamp for temporarily securing the apparatus in place, and features of adjustment enabling the grinding wheel to be brought into contact with each of the guide faces in turn, the attachment of the machine, the several possible adjustments, the movement of the grinding wheel toward and away from the surface to be ground, and the traverse of the wheel across the surface being within the ready control of the operating mechanic.

In the drawings accompanying the present specification, Figure 1 is a front elevation of a grinding apparatus embodying the present invention, the apparatus being indicated in a position ready for use. Fig. 2 is a plan view of Fig. 1. Fig. 3 is an horizontal section taken through the grinding wheel shaft in

Fig. 1. Fig. 4 is a detail view of one of the corrugated wear-pieces with which the members of the clamping jaw are provided. Fig. 55 is a cross section on the plane of the line 5—5 in Fig. 3.

Similar characters of reference designate corresponding parts in all figures.

While the present invention is applicable 69 to the construction of grinding apparatus susceptible of fulfilling various conditions in the arts, one of the most useful applications which we contemplate at the present time, is that of an apparatus for smoothing up the 65 joints in assembled elevator guide-sections, along which run the bearing shoes on the car or cage in the well.

Having premised the foregoing general scope of the invention, its description will, 70 for the purposes of explanation and intelligent comprehension, be given with reference to such particular use.

The usual form of elevator guide is T-shape, the guide shoes running along the web of the 75 guide. The present apparatus has a capacity, through manual manipulation, for grinding both the edge of the web as well as the opposite sides thereof, and it usually embodies a clamping device for securing the apparatus 80 adjacent to the joint on the guide at which the grinding is to be done. This clamping device may be of various constructions, that shown herein answering the purpose and comprising a pair of clamping jaws 2, 3, capable of being 85 drawn together by a binding screw 4, to clamp the jaws against the guide web. The unthreaded or upper portion of the shank of the binding screw fits somewhat loosely in the opening in the clamping jaw, and the 90 clamp carries at its outer end a setting-up screw 5, by which the outer ends of the jaw may be forced apart, and through a powerful lever-like action tighten the grip of the jaws on the web. Preferably, the inner faces of 95 the jaw between which the web is located, are provided with wear-resisting, friction-creating pieces, designed to increase the hold of the clamp on the opposite faces of the web. Such pieces may be in the nature of corrugated blocks of hardened steel, such as 6, 100 screw fastened to the inner faces of the jaws.

Jaw 2 is here provided with an enlargement or over-hanging boss 7, having a thread-

ed socket for the engagement of a screw 8, by means of which an arm 9 (carrying other portions of the apparatus) may be firmly secured to the clamp, or if the screw be loosened permit the arm to be angularly adjusted about the axis of the screw before being firmly fastened in position.

It should be here stated that the grinding wheel may be moved toward and away from the clamp, that is, lengthwise of the elevator guide faces, arm 9 conveniently supporting a guide bar along which this movement is made. This guide bar 10 is here shown as of angular or squared cross section, and is secured to arm 9 by any suitable means, that here illustrated embodying a nut 10'.

Slidably mounted on guide bar 10 is a sleeve 11, having heads 11', 11' at opposite ends. Between these heads there is journaled on the cylindrical surface of the sleeve a split clamp 12, having laterally extending ears 12', 12' connected by a clamping screw 12''. Rigid with this split clamp is a radial extension 13, formed at its end with a bearing 14, in which is slidably mounted a sleeve 15. Bearing 14 is separated throughout its length at one point in its periphery, and on opposite sides of the plane of separation are ears 14', 14' connected by a binding screw 14''. When this latter screw is unloosened, sleeve 15 may be slid lengthwise of the bearing; by tightening the screw, the sleeve may be clamped in its adjusted position. The sleeve may also be turned in the bearing to regulate the position of a grinding wheel shaft 16 mounted eccentrically in the sleeve.

Convenient grips or handles are provided for manipulating the parts during the progress of the grinding operation, that is, to carry the grinding wheel shaft 16 lengthwise of the guide bar 10, and to turn the sleeve 15 in its bearing to bring such shaft toward or away from the surface to be ground. The handles here shown comprise a wheel 17 secured to sleeve 15, and handles 18, 18 rigid with bearing 14.

Secured by any suitable means to shaft 16 is a grinding wheel 19. Preferably, a dust-proof joint is placed between shaft 16 and sleeve 15. In the construction here illustrated, a cup-shaped part 20 rigid with the grinding wheel is forced over a collar 21 rigid with shaft 16, the annular lip of part 20 extending over and forming a running fit with an extension of part 15 concentric with shaft 16.

Motion is transmitted to shaft 16 in any suitable manner, in this instance through a flexible shaft, not shown, which is connected with a bevel gear 23, mounted on an angle bracket 24, bored to fit over a part 25, concentric with shaft 16; gear 23 meshes with a companion gear 26 secured to the shaft 16.

It is evident from the foregoing description that when the clamp is secured to the

web of the elevator guide and screws 8, 12'' and 14'' are loosened, the grinding wheel may be brought close to the outer edge of the web with the wheel axis extending crosswise of and substantially parallel to the surface thereof; if screws 8 and 12'' are thereupon screwed down and the parts fastened, the surface may be ground by grasping either of the handles 18 and wheel 17, and moving the grinding wheel along the surface lengthwise and crosswise, sleeve 15 being turned sufficiently to give the desired cut. Or having rotarilly adjusted the sleeve to the proper extent, screw 14'' may be turned down to clamp the sleeve fast, and the parts moved lengthwise of guide bar 10. It is evident, moreover, that the angular character of this bar will hold the grinding wheel up to its work. A further adjustment of the parts by swinging arm 9, for instance, until the surface of the grinding wheel is brought in parallelism with one of the side faces of the elevator guide, will enable the grinding of such surface to be effected. The opposite face may be ground after a preliminary adjustment involving the removal of sleeve 11 from guide bar 10, the turning of the parts over, that is, upside down, and the reengagement of the sleeve with the guide bar. The present apparatus, therefore, obviously possesses a capacity enabling the grinding of both side surfaces as well as the edge surface of an elevator guide to be effected at one setting; that is when once the clamping device is secured in position, a few simple adjustments will permit the grinding wheel to be so shifted as to bring it into proper position for grinding said surfaces.

While handles have been specified and illustrated as aids in effecting movement of the grinding wheel longitudinally of the elevator guide, they may obviously be omitted if such movement is accomplished in other ways.

Having described our invention, we claim;

1. In a grinding apparatus, the combination of a guide bar, a grinding wheel shaft adjustable in a plane transverse to and about an axis coincident with the axis of said guide bar, and means for holding the shaft in its position of adjustment.

2. In a grinding apparatus, the combination of a guide bar of angular cross section, a grinding wheel shaft slidably mounted on said bar and adjustable in a plane transverse to and about an axis coincident with the axis of the bar, and means for holding the shaft in its position of adjustment in said plane.

3. In a grinding apparatus, the combination of a guide, a grinding wheel shaft extending transversely to and slidably mounted on said guide and adjustable in a plane transverse to said guide, a support for the apparatus, means extending between said guide and said support for adjusting the guide lat-

erally and holding it in its adjusted position, and means for holding said shaft in its position of adjustment in said plane.

4. In a grinding apparatus, the combination of a guide bar, a bearing whose axis is disposed at an angle to the axis of the bar, said bearing being slidably mounted on said bar and adjustable about the axis of said bar, means for holding the bearing in its position of adjustment about said axis, a grinding wheel shaft carried by said bearing, a support for the apparatus and means extending between said guide and said support for adjusting the guide laterally and holding it in its adjusted position.

5. In a grinding apparatus, the combination of a guide bar, a bearing whose axis is disposed at an angle to the axis of the bar, said bearing being slidably mounted on said bar and adjustable about the axis of said bar, means for holding the bearing in its position of adjustment about said axis, a grinding wheel shaft carried by said bearing, means for moving said shaft toward and away from the surface to be ground, a support for the apparatus and means extending between said guide and said support for adjusting the guide laterally and holding it in its adjusted position.

30 6. In a grinding apparatus, the combination of a laterally adjustable guide bar, a bearing whose axis is disposed at an angle to the axis of the bar, said bearing being slidably mounted on said bar and adjustable about the axis of said bar, a sleeve mounted to turn and to slide axially in said bearing, and a grinding wheel shaft eccentrically mounted in said sleeve.

7. In a grinding apparatus, the combination of a pivotally adjustable arm, a guide bar of angular cross section extending laterally therefrom, a bearing whose axis is disposed at an angle to the axis of the bar said bearing being slidably mounted on said bar and adjustable about the axis of the bar, a sleeve mounted to turn and slide axially in said bearing, and a grinding wheel shaft eccentrically mounted in said sleeve.

8. In a grinding apparatus, the combination of a clamping device, a guide bar adjustable laterally in a curved path about said clamping device, a bearing whose axis is disposed at an angle to the axis of the bar, said bearing being slidably mounted on said bar and adjustable about the axis of said bar, means for holding the bearing in its position of adjustment about said axis, and a grinding wheel shaft carried by said bearing.

9. In a grinding apparatus, the combination of a clamping device, a guide bar ad-

justable laterally in a curved path about said clamping device, a bearing whose axis is disposed at an angle to the axis of the bar, said bearing being slidably mounted on the bar and adjustable about the axis of said bar, means for holding the bearing in its position of adjustment about said axis, a grinding wheel shaft carried by said bearing, and means for moving said shaft toward and away from the surface to be ground.

10. In a grinding apparatus, the combination of a clamping device, a guide bar adjustable laterally in a curved path about said clamping device, a bearing whose axis is disposed at an angle to the axis of the bar, said bearing being slidably mounted on said bar and adjustable about the axis of said bar, a sleeve mounted to move in said bearing, and a grinding wheel shaft eccentrically mounted in said sleeve.

11. In a grinding apparatus, the combination of a clamping device, an arm pivotally adjustable thereon, a guide bar of angular cross section extending laterally therefrom, a bearing whose axis is disposed at an angle to the axis of the bar, said bearing being slidably mounted on said bar, and adjustable about the axis of the bar, a sleeve mounted to turn and slide axially in said bearing, and a grinding wheel shaft eccentrically mounted in said sleeve.

12. A grinding apparatus comprising in combination, a clamping device, an arm pivotally adjustable on said device, a guide bar of angular cross section secured to the arm, a sleeve slidably mounted on said bar, a split clamp rotatably mounted on said sleeve, a split bearing rigid with said split clamp, a sleeve mounted in said bearing, a shaft eccentrically mounted in said latter mentioned sleeve, and operating handles substantially as set forth.

13. In a grinding apparatus, the combination of a clamping device, a grinding wheel, and means of adjustment comprising two axes of adjustment parallel to the plane of rotation of the grinding wheel whereby said wheel may be positioned at one setting of the clamping device to grind surfaces whose planes are disposed at an angle to each other.

In testimony whereof we have signed our names to this specification in the presence of two subscribing witnesses.
